ELECTRIC SWITCH

Henry C. Sway, Bridgeport, Conn., assignor to
General Electric Company, a corporation of
New York

Application March 26, 1952, Serial No. 278,657

5 Claims. (Cl. 200—164)

1

This invention relates to electric switches, more particularly to such switches having a pair of coacting contact elements, and its principal object is to provide such a switch wherein failure of the contacts to close due to an accumulation of foreign matter on the surfaces of the contacts, as dust or an oxide of the material of which the contacts are made, is substantially eliminated.

More specifically, this invention has for an object the provision of an improved electric switch embodying improved contact structure and means for effecting a sliding or wiping motion between the contacts as they open and close so as to effect a cleaning action and thereby prevent the accumulation of foreign matter between them.

In accordance with my invention, I provide an elastic arm which carries one of the switch contacts. This contact is mounted on a portion of the arm which is bowed with respect to the main body of the arm, as by angularly relating that portion to the main body, and it engages a fixed contact whose contact area is substantially parallel to the angled portion of the arm; and the bias of the arm holds the contacts in engagement. An actuating element engages the body of the arm to move it to effect separation of the contacts and to permit it to move to reclose them. But its motion to open the contacts is resisted by a second elastic member which engages the arm substantially at the juncture point between the main body of the arm and its angularly deflected contact carrying portion; and also is arranged to bias the contacts closed. And its tension is such that the switch arm when operated to open, first warps about the second elastic member as a fulcrum before the contacts open, thereby to wipe or slide its contact across the face of the other contact, and only after this happens does the second elastic member yield to permit the contacts to open. Moreover, the parts are so arranged that the contact pressure is actually increased by the action of the second or pressure applying elastic member during the wiping stage of the opening operation. Likewise when the contacts close, they close with a wiping action.

My invention will be better understood from the following description taken in connection with the accompanying drawing and its scope will be pointed out in the appended claims.

In the drawing, Fig. 1 is a plan view of an electric switch embodying this invention; Fig. 2 is a vertical sectional view taken through the line 2—2 of Fig. 1 and looking in the direction of the arrows; Fig. 3 is a fragmentary sectional view similar to Fig. 2 illustrating the switch in its closed position and drawn to a larger scale than Figs. 1 and 2; Fig. 4 is a sectional view similar to Fig. 3 but illustrating the switch elements at one stage of the opening operation; and Fig. 5 is a

2

view similar to Figs. 3 and 4 but illustrating the switch contacts in their open position.

Referring to the drawing, this invention has been shown in one form as applied to an electric switch comprising a base 1 formed as a flat plate having parallel upper and lower flat surfaces; this plate may be formed of any suitable electrically insulating material such as a suitable electrically insulating plastic. Mounted upon the 10 plate 1 is a fixed contact 2 formed of any suitable material such as silver, and in the shape of a rivet, and mounted in rivet-like fashion upon a supporting bracket 3; the bracket 3 is of angular shape, as shown, having a base portion 15 4 and an upwardly extending contact supporting section 5 arranged at an angle to the base 4 so that it supports the contact 2 with its engaging face at an angle of substantially 45° to the top surface of the base 1. The base 4 has one end 20 portion, the lower end portion, as viewed in Fig. 1 wrapped around that edge of the base 1, and its other end 6 constitutes a terminal connection for the fixed contact 2; the wrapped portion of base 4 is inserted in a recess 5a provided in the edge 25 of plate 1 so that it is secured against turning with respect to the plate. The bracket 3 as a whole is riveted to the base 1 by means of a rivet 7, and this rivet 7 also forms the terminal connection for an electrical supply conductor 8 which 30 it will be understood will be connected in a suitable electrical circuit to be controlled.

Also mounted upon the base 1 to coact with the fixed contact 2 is a movable contact 9 similar to the contact 2. The contact 9, however, is 35 mounted upon an elastic switch arm 10 which by its inherent resiliency tends to maintain the two contacts in closed position, as shown in Figs. 2 and 3. The contact arm 10 is in the form of a relatively elongated strip extending lengthwise 40 across the top of the base 1 from the contacts toward the left of the plate, as shown, where its left-hand end is anchored to the base 1 through the medium of a suitable terminal plate 11; as shown, the left-hand end of the switch arm is 45 connected to the terminal plate 11 by means of a suitable rivet 12; the arm 10 is prevented from rotating with respect to the terminal plate 11 by means of a tongue 13 formed on and extending upwardly from the terminal plate and received in a slot 14 provided for it in the end of 50 the contact arm. Here again the terminal plate may be connected to a suitable external conductor 15 by means of a suitable rivet 16 which rivet also functions to secure the terminal plate 11 to the base 1 and thereby also serves to connect the switch arm 10 to the base 1. This terminal plate like the terminal plate 6 also has one end, its lower end as viewed in Fig. 1, wrapped around the lower edge of the plate in a 55 recess 17 provided for in the plate so as to pre- 60

vent twisting or turning of the terminal with respect to the base.

The left-hand end of the switch arm 10 is clamped to the plate so as to bias the contacts 2 and 9 closed, as previously pointed out. As shown, the switch arm 10 extends across the top surface of the base 1 relatively close to it but not quite in parallel relation therewith, but tapering upwardly therefrom somewhat as the arm approaches the contacts. The right-hand end of the switch arm is provided with a contact supporting portion 18 deflected upwardly at an angle to the main body portion of the arm to have an angle of substantially 45° with the top surface of the base 1 when the contacts are closed; that is, the deflected portion 18 supports the contact area of the contact 9 in a plane substantially 45° to the top surface of the base 1, that is, parallel to the contact area of the contact 2. Thus the contact bearing portion 18 of the arm 10 is deflected therefrom at a juncture point 19 so as to support the contact area of contact 9 in the fashion heretofore described.

There is provided a second relatively elongated elastic member 20 clamped at its left-hand end, as viewed in Figs. 1 and 2 to the top surface of the left-hand end of the contact arm 10 by means of the rivet 12 and which also is prevented from twisting with respect to the base 1 by means of the tongue 13 provided on terminal plate 11 and extending up through a slot 21 provided for it in the left-hand end of the elastic member 20. As shown, the elastic member 20 from the point where it is clamped to the arm 10 slants upwardly away from the arm throughout substantially the entire length of the body portion thereof, but at its right-hand end it curves downwardly to engage the switch arm 10 at the juncture point 19. Elastic member 20 is arranged to apply its elastic force downwardly, that is, it adds its force to that of the arm 10 in order to force the contacts 2 and 9 closed. The elastic member 20 is relatively more rigid; that is relatively more unyielding than is the switch arm 10.

In the operation of the switch, there is provided means for actuating the two arms 10 and 20 upwardly thereby to effect an opening movement of the contact 9. This means comprises a plunger 22 in the form of a rod or pin which is directed upwardly through an aperture 23 provided for it in the base 1 positioned so that when it is moved upwardly it will engage the lower surface of the right-hand end portion of the main body part of the switch arm 10 which, of course, will be located to the left of the juncture point 19 where the pressure elastic member 20 engages the arm 10.

In operation, when this plunger 22 is moved upwardly, as viewed in the drawings, from its position of Fig. 3 to its position of Fig. 4, it will first engage the arm 10 and tend to move it upwardly. Upward movement of the arm 10, however, is resisted by the pressure arm 20 and since the arm 20 is relatively more unyielding than is the arm 10, the first upward movement of the pin 22 fulcrums or warps the arm 10 so to speak about the free end of the pressure arm 20 which operation will tend to straighten out the arm 10 somewhat from its position of Fig. 3 to its position of Fig. 4; this operation slides the contact 10 upwardly to the right as viewed in Fig. 4 by distance x measured between the two dot and dash lines which pass through the centers of the contacts respectively, and rocks it slightly as it slides it. In other words, this action causes the

contacts to wipe by this amount x . Fig. 4 illustrates the condition just at about the time the switch contacts tend to open; in other words after the arm 10 is straightened out to the degree shown in Fig. 4 continued upward movement of the plunger 22 will move the two arms 10 and 20 together as a unit upwardly thereby effecting a separation of the contacts as shown in Fig. 5. The distance y between the two dot and dash lines in Fig. 5 indicates the degree of displacement of the contact 9 from its central closed position of Fig. 3. Likewise when the contacts move to their closed position (the operation effected by withdrawal of the pin 22), the contact 9 will move back through this distance y to its completely closed position, and again the pressure arm 20 will bow the contact arm 10 downwardly as shown in Fig. 3.

It will be observed that by reason of the warping or fulcruming of the arm 10 about the arm 20 in the opening operation the contact pressure actually is increased during the opening operation, that is, during that portion thereof when the contact 9 is sliding and rocking with respect to the contact 2. This wiping action is enhanced by the angular arrangement of the contacts 2 and 9 with respect to the base 1; and also the contact pressure at the start of the contact opening operation is increased by this angular relationship.

The sliding action effected between the contacts and the increased pressure effected between them during the sliding operation effectively and positively cleans the contacts and prevents the accumulation of dust and the oxide of the metal of which the contacts are formed. In addition, to this the inclined relationship of the two contacts prevents the accumulation of dust between them.

Another important feature of this invention is the suppression of contact "bounce." Often-times heretofore in the case of rapidly operating contacts there is a bounce on the initial contact between the contacts as they close, which bounce opens the circuit after it should be closed. This creates undue arcing and circuit disturbance. The double elastic arm arrangement 10, 20 of this invention cushions the initial impact, and the angle arrangement of the contacts further tends to dampen the vibrations.

It will be obvious, of course, that any suitable mechanism may be provided for operating the pin 22; it may be manually or electro-magnetically operated; or it may be operated by a suitable thermal responsive control element (not shown).

This invention provides a switch which has a high rate of contact wipe in a small, compact space, with relatively small contact actuating movement, and with comparatively light contact pressures.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States is:

1. Switch structure comprising a relatively elongated elastic switch arm having one end portion formed in a plane lying at an angle to the remaining body portion thereof, a contact on said one end portion, a fixed contact engageable

by said contact, means anchoring the other end of said arm so that it biases said contacts together with a predetermined force, biasing means applying an elastic force to said arm substantially at the juncture of said body and end portions to increase the pressure between said contacts, and an operating element for applying a force to said arm intermediate its said other end and said juncture to open said contacts, said biasing means applying an elastic force of such magnitude that initially it resists movement of said arm away from said fixed contact whereby said arm flexes to effect relative shifting movement and increased pressure between said contacts prior to their opening and thereafter yields to permit opening movement of said arm.

2. Switch structure comprising a base, a fixed contact on said base having a contact area in a plane at an acute angle to said base, an elastic switch arm lying over said base having an end remote from said contact fixed to said base and its other end portion adjacent said contact, said latter end portion being deflected outwardly from the body of said arm to lie in a plane substantially parallel to said first plane and having a contact area engageable with said fixed contact area, the resiliency of said arm biasing said contacts together, a second elastic arm relatively unyielding as compared with the first having one end remote from said contact secured to said base and its other end engaging said first arm at the juncture thereof with its deflected contact end portion and biasing said arm to increase said contact pressure, and an actuating member engageable with said first arm at a point intermediate its fixed end and said juncture to move it away from and to permit it to return toward said base thereby to open and reclose said contacts, said second elastic arm applying an elastic force of such magnitude that initially it resists movement of said first arm away from said fixed contact whereby said first arm flexes to effect relative shifting movement and increased pressure between said contacts prior to their opening and thereafter yields to permit opening movement of said first arm.

3. Switch mechanism comprising a flat base, a fixed contact on said base having a contact area lying in a plane substantially 45° with said base, an elastic switch arm having one end fixed to said base extending from said end across said base toward said fixed contact where its other end deflects outwardly from the base at an angle of substantially 45° , said latter end carrying a contact area biased into engagement with said fixed contact area by said elastic switch arm, a second elastic arm relatively unyielding as compared with the first having one end remote from said contacts secured to said base and its other end engaging said first arm at the juncture thereof with its deflected contact end portion and biasing said first arm to increase said contact pressure, and an actuating member engageable with said first arm at a point intermediate its fixed end and said juncture to move it away from and to permit it to return toward said base thereby to open and reclose said contact areas, said second elastic arm applying an elastic force of such magnitude that initially it resists movement of said first arm away from said fixed contact area whereby said first arm flexes to effect relative shifting movement and increased pressure between said contact areas prior to their opening and thereafter yields to permit opening movement of said first arm.

4. Switch structure comprising a base having a flat supporting surface, a fixed contact member on said surface having a contact area lying in a plane forming an acute angle with said surface, a pair of superimposed elastic arms on said base attached together and to said surface at one end, the outer arm being relatively more rigid than the inner arm and both biased toward said surface, and the outer arm curving outwardly away from the inner arm from their fixed ends to a point adjacent the other end portion of the inner arm where it curves inwardly to engage said inner arm, said other end portion of said inner arm deflecting outwardly at the point of engagement between said arms at an acute angle with respect to said surface, which angle is substantially the same as said first mentioned acute angle, a contact on said deflected end engageable with said fixed contact area, and an actuating member engageable with said inner arm intermediate its fixed end and said point of engagement to operate it to effect the opening and closing of said contacts, said outer arm applying an elastic force of such magnitude that initially it resists movement of said inner arm away from said fixed contact whereby said other end portion pivots about said point of engagement to effect relative shifting movement and increased pressure between said contacts prior to their opening and thereafter yields to permit opening movement of said inner arm.

5. Switch structure comprising a base having a plane supporting surface, a fixed contact arm on said surface having a contact area lying in a plane substantially 45° to said surface, an elastic switch arm relatively long as compared with its width extending lengthwise along said surface and having one end adjacent said fixed contact area deflected outwardly at an angle to the body portion of said arm so as to be substantially parallel to said fixed contact area and having a contact area engageable with said fixed area, means anchoring the other end of said arm to said surface to flex said arm to bias said contact areas together with a predetermined force, a second elastic arm relatively more rigid than the first substantially coextensive with the body portion of the first and spaced therefrom substantially throughout its length but having one end engaging said first arm at the juncture between the body thereof and its deflected end portion, thereby to act as a fulcrum for said first arm, means anchoring the other end of said second arm to said base to cause it to engage said juncture with a predetermined force, and an actuator engageable with said first arm at a point intermediate said juncture and its said other end to effect the opening and closing of said contacts, said second elastic arm applying a force of such magnitude that initially it resists movement of said first arm away from said fixed contact whereby said deflected end portion pivots about said juncture to effect relative shifting movement and increased pressure between said contacts prior to their opening and thereafter yields to permit opening movement of said first arm.
